UNITED STATES PATENT OFFICE.

DAVID LEONARD BARNES, OF CHICAGO, ILLINOIS, ASSIGNOR TO THE CONSOLIDATED COUPLING COMPANY, OF NEW JERSEY.

CAR-COUPLING.

SPECIFICATION forming part of Letters Patent No. 407,808, dated July 30, 1889.

Application filed September 7, 1888. Serial No. 284,846. (No model.)

To all whom it may concern:

Be it known that I, DAVID LEONARD BARNES, a citizen of the United States, and a resident of Chicago, in the county of Cook, 5 State of Illinois, have invented certain new and useful Improvements in Car-Couplers, of which the following is a specification.

My invention has special reference to the construction of vertical-plane couplers of the 10 type generally known as the "Dowling" coupler.

My invention relates to various details of construction, which will be hereinafter specifically mentioned, whereby the coupling is 15 made stronger and better able to meet the conditions required in practice.

My improvements may be divided into two parts, the first relating to the configuration of the draw-head and coupling-hook and the 20 second to the locking device for the coupling-hook.

I will first describe my invention in connection with the drawings, in which similar letters of reference indicate like parts, and 25 then specifically point out what I claim as my invention.

Figure 1 is a view showing two couplers in the position they would occupy when coupled. The left-hand coupler is shown in horizontal 30 section and the right as a plan view. Fig. 2 is a similar view showing a modification of the draw-head and coupling-hook. Fig. 3 is a vertical section taken on the line X X of Fig. 1. Fig. 4 is a plan view of the coupling-hook. Fig. 5 is an elevation of the inner side 35 of the knuckle. Fig. 6 is an elevation of the outer side of the knuckle. Fig. 7 is a transverse vertical section on the line Y Y of Fig. 1. Fig. 8 is an elevation of the coupling-pin.

A represents a draw-head, which may be of 40 any suitable material, preferably of malleable iron or cast-steel. At one side of the draw-head is an arc-shaped slot B, located between the walls B' B''. Near the outer end of the 45 wall B'' is the cylindrical projection C, which forms the center of rotation for the knuckle D. The top and bottom plates of the draw-head are likewise provided with bearing-shoulders E, projecting into the arc-shaped 50 slot, which shoulders are concentric with

similar shoulders F upon the knuckle D, both of which shoulders are concentric with the point of rotation C of the draw-head. In Fig. 2, however, the bearing-shoulders E are not shown, and in place thereof, in order to provide means for resisting the traction strains to which the knuckle is subjected, is the boss or projection R, extending inwardly from the wall B'' and taking into the cavity D' provided to receive it in the stem of the 60 knuckle D.

The knuckle D corresponds in all respects with the knuckles heretofore used in couplers of this class—that is to say, it has a hook-head and stem which works in an arc-shaped 65 slot—the only difference being that the end of the knuckle is carried outward and backwardly as the projection D'', which projects from the arc-shaped portion of the knuckle and lies wholly without the arc of rotation of 70 the arc-shaped portion. Through this projection is an opening P, through which the locking-pin passes.

Immediately under the end of the projection D'' and in the bottom plate of the draw-head is the slot H. This slot is concentric with the arc-shaped slot B and is inclined downwardly from the side of the coupler toward the center. The object in providing the projection D'' is to decrease the leverage on 8c the locking-pin. In couplers of this class the locking-pin has been located approximately at the point Z of Fig. 2, and when so located was subjected to very heavy strains by any force exerted at the end of the hook D. By 85 moving the point of resistance back to W the leverage is decreased, and I am enabled to provide a stronger lock and one better able to resist the strains usual in practice with couplers of this description.

The locking device which I propose to use is shown in Figs. 3 and 8, and consists of the cylindrical pin divided into three portions G G' G''. The part G corresponds in width with the tongue or projection D'' on the stem of 95 the knuckle. The part G' is supported above the stem of the knuckle by the pin S, which moves in a slot O. A similar pin S' moves in a similar slot O' and supports the part G''.

V represents a lever pivoted at T, the end 100

of which U bears on the under part of the pin G². By depressing the lever V until the point U strikes against the projection K in the bottom plate of the draw-head, and as shown in 5 the dotted lines, the sectional pin is elevated until the edges of the pin G register with those of the projection D², when the knuckle can be opened. The limit of movement of the parts of the pin is regulated by the length of 10 the slots O and O' in the parts G' and G².

When the knuckle is rotated to open the 15 coupler, the pin G moves inwardly and downwardly in the slot H, striking against the end of the slot, when the full outward movement 20 of the hook is accomplished, thereby limiting the range of movement of the knuckle.

The tongue D² has less vertical depth than the balance of the stem, and hence as the 25 knuckle moves outwardly the part of the pin G' moves downwardly into the position which it ordinarily occupies when the hook is locked. As the tongue moves inward it strikes this pin, which is inclined, as shown at G³, and which is moved upward by the inner movement of the tongue D².

I have not considered it necessary in this 30 specification to enter into a detailed description of all the various features of the coupler, for the reason that the same have been fully 35 described in Letters Patent heretofore granted to Dowling and others.

I claim as my invention—

1. In a car-coupler, the combination, with a 35 draw-head having an arc-shaped slot formed therein, of a movable knuckle provided with

an arc-shaped stem and a tongue or projection extending from said stem, through which is made an opening for receiving a locking device, substantially as described.

2. In a car-coupler, and in combination with 40 a draw-head having an arc-shaped slot formed therein, an inclined slot concentric with such arc-shaped slot, a movable knuckle provided with an arc-shaped stem, a projection or tongue on the end of said stem, and a locking device 45 one portion of which is adapted to engage with said inclined slot in the draw-head, substantially as and for the purpose described.

3. In a car-coupler, the combination, with a 50 draw-head and the movable knuckle thereof, of a sectional coupling-pin, substantially as described.

4. In a car-coupler, the combination, with a 55 draw-head and the movable knuckle thereof, of a vertically-acting sectional coupling-pin and the means for limiting the motion of the pin, consisting of the pins S and S' and slots O and O', substantially as described.

5. In a car-coupler, the combination, with a 60 draw-head and knuckle thereof, and with the sectional coupling-pin substantially of the character indicated, of the lever adapted to give motion to said pin, substantially as described.

In witness whereof I have hereunto set my 65 hand.

DAVID LEONARD BARNES.
